CLAIM

The ornamental design for a bracelet connector, as shown and described.

DESCRIPTION

FIG. 1 is a perspective view of a bracelet connector; FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines shown in the drawings depict a bracelet that forms no part of the claimed invention.
